UNITED STATES PATENT OFFICE.

KARL WILHELM LJUNGEDELL, OF MÄLMO, SWEDEN.

BUILDING OF CONCRETE SHIPS, LIGHTERS, AND OTHER CONCRETE CONSTRUCTIONS.

1,320,880.

Specification of Letters Patent.

Patented Nov. 4, 1919.

Application filed April 10, 1918. Serial No. 227,756.

To all whom it may concern:

Be it known that I, KARL WILHELM LJUNGEDELL, a citizen of Sweden, residing at Villa Klara hill, Malmö, Sweden, have 5 invented certain new and useful Improvements in the Building of Concrete Ships, Lighters, and other Concrete Constructions, of which the following is a full, clear, and exact description.

10 The present invention relates to certain improvements in the building of light concrete constructions, such as ships, lighters and the like without using an ordinary frame work and without any false work 15 construction or molds.

The invention is illustrated in the accompanying drawing. Figure 1 shows the framing for a concrete construction according to the invention, and Fig. 2 shows a 20 cross section of a hull of a ship.

According to the invention the concrete is applied on a frame that is left in the concrete after it having served as support and form for the construction. Thus the entire 25 weight of the construction will be reduced, and the framing serves also to strengthen the construction immediately after the erection, for instance during the launching of a new built concrete ship or the like, when 30 the launching takes place before the concrete has hardened completely.

In the form shown in the drawing the framing or skeleton consists of a number of wooden logs 1 parallel with each other 35 and placed at some distance from each other, said logs being connected with each other in a suitable way and kept from each other by means of wooden blocks 2 or the like placed a suitable distance from each other 40 in order to procure interspaces between the logs for the application of the concrete mass and for effecting connecting material between the inner and outer concrete layers. The logs are placed in such a way 45 in sets that their ends do not lie opposite each other but break joint, as shown in Fig. 1. Reinforcement bars 3 are arranged at suitable places and at a suitable distance from the logs on one or both sides of the 50 framing, and these reinforcement bars are kept in position during the applying of

the concrete mass by means of cramps 5 or the like driven into the framing. On the sides of the framing, for instance on its outside a wire netting 4 may be applied for 55 keeping the concrete mass without using molds. After the concrete has been applied it is smoothed on the outside. The edges of the logs ought to be beveled, as shown in the drawing, in order to strengthen 60 the concrete parts in these places. Thus a construction is obtained consisting of a number of I-girders placed beside each other of which the webs consist of the concrete filled in between the logs. 65

By the new invention the advantage is gained that the reinforcement metal, the concrete mass and the wire netting easily may be applied and kept in their positions during the filling of the concrete. 70

What I claim as new and desire to secure by Letters Patent is:

A ship hull comprising a concrete wall, a plurality of vertically spaced longitudinal sets of logs embedded within the wall near 75 the central portion thereof, the logs in the different sets having their ends arranged to break joint, each log having its four corners beveled whereby the portions of the concrete wall between the logs are I-shaped in 80 cross section for providing a construction which is strong and which positively interlocks with the logs, spacing blocks arranged between the sets of logs, substantially vertical reinforcing rods embedded in the inner and outer portions of the wall and arranged upon opposite sides of the logs, means for tying the reinforcing rods to the 85 logs, substantially horizontal reinforcing rods embedded in the wall and arranged between the outer beveled edges of the logs, and a wire netting embedded in the outer portion of the wall and disposed outwardly of the outer substantially vertical reinforcing rods. 90

In testimony whereof, I have signed my name to this specification in the presence of two subscribing witnesses.

KARL WILHELM LJUNGEDELL.
